UNITED STATES PATENT OFFICE.

JAMES WILKINSON, OF SCHENECTADY, NEW YORK, ASSIGNOR TO GENERAL ELECTRIC COMPANY, A CORPORATION OF NEW YORK.

PACKING FOR ELASTIC-FLUID TURBINES.

1,021,225.

Specification of Letters Patent. Patented Mar. 26, 1912.

Application filed October 12, 1911. Serial No. 654,383.

To all whom it may concern:

Be it known that I, JAMES WILKINSON, a citizen of the United States, residing at Schenectady, county of Schenectady, State 5 of New York, have invented certain new and useful Improvements in Packings for Elastic-Fluid Turbines, of which the following is a specification.

My invention relates to packings for elastic fluid turbines or rotary motors, and has 10 for its object to improve their construction whereby they are rendered more effective in service.

My invention also comprises improvements in the turbine which relate to the 15 manner of constructing the diaphragms and outer shell, the liquid sealing device and of forming a dead air chamber opposite that portion of the inner casing where the highest 20 temperatures obtain.

The improvements constituting the subject-matter of my present invention have been illustrated in one form in the accompanying drawings, but they are not to be 25 construed as limited by the construction or arrangements of parts therein appearing, the same being only illustrative of that which is hereinafter claimed as my invention.

Referring to the drawings which illustrate one embodiment of my invention:—Figure 1 is a vertical sectional elevation through a turbine provided with my improved packing devices shown in elevation; 30 Fig. 2 is an enlarged detail view of part of the packing comprising the rotating rings and the novel manner of forming the grooves and conduits therin for returning the leakage to the turbine; Fig. 3 is an end 35 elevation of Fig. 1, the motor for adjusting the packing being shown in section; and Fig. 4 is an end view of Fig. 2, with the inner stationary ring removed.

Similar reference numerals refer to similar parts throughout the drawings.

The turbine in connection with which I have illustrated my invention comprises a supply head 1 and a plurality of interlocking diaphragms 2, which are engaged and held between abutments 3 on an outer casing 4, divided into half sections on a horizontal plane and provided with flanges 5, bolted together as seen in Fig. 3. The upper half is provided with eye bolts 6, by means

of which it may be lifted when it is desired to gain access to the inner casing or interior of the turbine. An exhaust head 7 is bolted or otherwise secured to the outer casing 4 and communicates with a condenser or the atmosphere, as the case may be. In the present construction my turbine is designed to operate non-condensing. The several diaphragms increase in diameter toward the low pressure end, a dead air chamber 8 being provided between the peripheries of the high pressure diaphragms and the casing.

The several diaphragms 2 divide the interior of the turbine into stages, within each of which a wheel 9 rotates, having suitable buckets which are disposed opposite to, and are driven by the motive fluid flowing through the several nozzle passages 10 which lead from a supply passage 11 in the head 1. A port 12 admits motive fluid to the passage 11. The several bucket wheels have abutting hub portions rigidly mounted upon a shaft 13 which passes through the supply and exhaust heads and is supported in suitable bearings 14 and 15. When the turbine is adapted for marine propulsion, a propeller 16 may be connected to the shaft 13, which will be provided with thrust collars 17, where it passes through the thrust bearing 15. The several diaphragms extend close to the abutting hub wheels, leaving as small a clearance as is consistent with safety when in operation.

The supply head 1 is provided with an enlarged central opening for the shaft 13, the inner end of this opening having a coarse screw thread 18. A non-rusting bushing 19 is inserted in the opening in the head and provided with threads which engage the screw threads 18 and permit of its adjustment longitudinally of the shaft. A gland 20, adjusted by screws, forces the packing 21 between the sleeve and the head to prevent leakage of fluid passing the threads 18. The bushing 19 which is in halves or otherwise split, is provided with a plurality of inwardly disposed annular projections or rings 22 which may be formed integral therewith or halved and inserted in annular grooves therein as shown. A sleeve 23 is mounted on the shaft within the bushing 19 and arranged so that it abuts the hub of the first wheel 9 and rotates therewith. Annular rings 24 on the sleeve 23 are inter-

posed between the rings 22, forming a tortuous gland or ring and groove packing—sometimes called a labyrinth packing. Beyond the sleeve 23 I provide a chamber 25 surrounding the shaft and supplied with liquid such as water, which is acted upon by a centrifugal pump element 26. This element rotates with the shaft and acts upon the body of liquid to cause it to seal the joint between the shaft and the bushing 19, and prevent leakage to or from the atmosphere. The low pressure end of the turbine is provided with a similar chamber 25 and element 26, the chamber being provided with removable side walls 27 and 28.

Referring to Fig. 2, it will be seen that the right-hand face of each of the rotating rings 24 is provided with a circumferential groove 29, so disposed with relation to the several outer rings 22 as to be more or less throttled by said rings according to the relative positions of the bushing 19 and sleeve 23. I provide passages 30 which lead from the grooves 29 in the rings 24 and at right angles through the sleeve 23, being adapted to register with the passages 31, indicated in dotted lines Fig. 1, which lead through the abutting wheel hubs and open into the several stages of the turbine, excepting the initial stage. In the contemplation of my present invention, these passages may be formed in any desired manner and lead to any desired points in the turbine.

I consider it preferable that the passages 30, leading from each of the packing ring chambers, should discharge substantially equal parts in weight of the leakage fluid back into the turbine. Inasmuch as a given weight of fluid will be of greater volume at the low pressure end of the packing than at the high pressure end, it follows that provision should be made to increase the area of the passages leading to the low pressure stages. This is best done by providing a larger number of passages 30 for the low pressure stages, although the same effect may be obtained, where the same number of passages lead from the several stages, by increasing the area of the passages or both of these arrangements may be combined as to area and number of the passages. As shown in Fig. 2, I provide the first three rings 24 at the high pressure end of the packing with one passage 30 each, and the succeeding rings with two passages each, preferably leading from diametrically opposite points in each ring.

To govern the leakage of fluid through the ring packing, I provide means responsive to changes of pressure in the packing for adjusting the bushing 19 so as to vary the clearances between the rings. This mechanism comprises a cylinder 32, Fig. 3, bolted to the lower half of the casing 4 and disposed substantially horizontally. A

trunk piston 33, which moves pressure tight within this cylinder, is pivotally connected to a piston rod 34, which leads through an enlarged opening in the screw head 35 for the cylinder and is pivotally connected at its outer end to a lever 36, bolted or otherwise connected to the bushing 19. As seen in Fig. 3, this bushing is formed in halves bolted together and is closed at its outer end by an annular plate 37, which forms the outer side wall for the liquid packing chamber 25. A flexible tube 38 leads from the closed end of the cylinder 32 to the outer end of the bushing 19, where it connects with a coupling screwed into the outer end of a passage 39, Fig. 1, leading through the shell and entering one of the low pressure ring chambers, hereinafter referred to as the "governing ring chamber 46". This tube may be provided with a valve if needed. It is to be noted that the motor depends for its action on the steam which escapes from the chamber 46. The head 35, for the motor cylinder, is adjustable so as to vary the tension on a spring 40, which engages the piston 33 and tends to move it with the desired force against the fluid pressure from the governing ring chamber 46 admitted through the tube 38. Any movement of the piston through the connections described, serves to oscillate the bushing 19 which, being screwed into the head, will be adjusted longitudinally of the shaft by such rocking movement. The travel of the piston and the pitch of the threads 18 being determined with relation to each other and the clearances between the rings 22 and 24, it follows that the movements of the piston may be such as to practically close the clearances between the rings as the pressure in the packing rises, or to open these clearances to any desired degree as the pressure falls. The arrangement of parts will be such that the outer rings 24 can not be moved so close to the rings 22 as to cause dangerous contact. Adjustable travel limiting means for the motor and means to lock the motor or packing in any position may be provided.

The liquid packing devices may be of any suitable form. This packing is designed to operate between low pressures, such for instance as differences in pressures of less than twenty pounds per square inch, hence every precaution should be taken to prevent exposing it to an internal pressure sufficient to blow out its sealing liquid. The automatic adjustment of the bushing rings 22 relatively to rotating rings 24 contributes to this end, as to also the passages 30 and 31. In addition to this I provide two passages 41, Figs. 2 and 3, which lead from the low pressure end of the packing sleeve 23 through the several wheel hubs to the exhaust end of the turbine, thereby acting

to exhaust the fluid which may leak past the ring packing and draw off surplus water of condensation.

The tendency of the self adjusting ring packing being to maintain a substantially constant pressure in the "governing ring chamber 46," it follows that, as the internal pressure, against which the packing acts, rises or falls, the automatic devices will act to adjust the ring clearances responsive thereto. Thus, as the first stage pressure falls, the ring clearances are increased, thereby permitting a greater volume of fluid to flow through the ring chambers to hold up the pressure in the governing ring chamber 46. Also when the turbine pressure becomes excessive, the ring clearances are reduced to such an extent that the motive fluid may even flow back from the turbine through the passages into the low pressure ring chambers. Since the passages 30 are designed to discharge given portions of the leakage fluid under predetermined conditions of pressure in the turbine, some provision should be made to keep their cross-sectional area proportioned to the cross-sectional area of the ring clearances, otherwise, if the governing ring chamber be subjected to comparatively high pressure, its pressure may remain substantially constant while the pressure in the succeeding ring chambers becomes excessive, due to the accumulation therein of more fluid than can be discharged through the passages 30 and 31, or to the reverse flow of fluid from the turbine through said passages. As a result of these conditions the terminal pressure of the leakage fluid, acting against the liquid seal may rise and blow out the sealing liquid. To prevent this, I utilize, as a governing ring chamber, one whose normal pressure is but slightly above that of the atmosphere or which is below the power of the liquid seal as chamber 46 for example. By taking said low pressure ring chamber as a governing chamber, I secure the maximum range of governing effect over the packing rings and also insure that no greater pressure will occur against the liquid seal than it can safely pack against. I also so arrange the passages 30 that their available area for the discharge of leakage fluid, or their capacity, is influenced by the adjustment of the packing. This is effected by the arrangement of the grooves 29, from which the passages 30 lead, being so disposed with relation to the adjacent rings 22, as to wiredraw or throttle the steam as the rings approach. This arrangement enables me to preserve the proportion between the areas of the ring clearances and the passages 30. It also provides an automatic valve control both of the fluid leaking through the packing and of the flow of fluid therefrom into the turbine, or from the turbine into the packing. I can

govern all fluid which has access to the liquid seal and keep it within the desired pressure limits.

The cylinder head 35 is provided with notches for the reception of a spanner wrench 42, by means of which the tension of the spring 40 may be adjusted by hand as desired. To drain the water or leakage from the chamber 8 and of condensation from the exhaust head, I provide these parts 75 respectively with drains 43 and 44.

One of the material advantages of my improved packing resides in the fact that the member which is adjusted axially to change the clearances is relatively small and requires only a small expenditure of power to move it. This means that the rotor can remain in a fixed position which is important where the bucket clearances are small. It is also important in those cases where the rotor 85 is fixed in position as by the use of a thrust block and where it would be impractical to adjust it for variations in leakage.

In accordance with the provisions of the patent statutes, I have described the principle of operation of my invention, together with the apparatus which I now consider to represent the best embodiment thereof; but I desire to have it understood that the apparatus shown is only illustrative, and that 95 the invention can be carried out by other means.

What I claim as new and desire to secure by Letters Patent of the United States, is:—

1. In an elastic fluid turbine, a casing, a 100 rotatable element driven by the motive fluid therein, and a high pressure packing for said rotatable element comprising an adjustable element which moves independent of the rotor and responsive to variations in 105 pressure at or near the low pressure end of said packing and governs the leakage of fluid through said packing.

2. In a turbine, a high pressure head therefor provided with a shaft opening, a 110 shaft, extending through said opening, and a compound throttling packing for the clearance between said shaft and head, said packing comprising an element adjustably connected to the head and movable responsive 115 to the pressure of the leakage fluid to throttle said fluid at different points in the packing.

3. In a turbine, a casing, rotatable parts therein, a shaft supporting said parts and passing through said casing, means to prevent leakage of high pressure fluid between said shaft and casing comprising a rotary and a stationary element forming a tortuous passage, and a fluid motor movable responsive to pressure variations at or near the low pressure end of said packing, which adjusts said stationary element. 120

4. In a turbine, a supply head, a shaft extending through an opening in said head, 130 packing rings rotatable with the shaft,

- 4 bushing supported by the head, internal ring projections in said bushing which are interposed between the projections rotatable with said shaft, and a fluid motor controlled by the leakage fluid and adapted to adjust said bushing axially of the shaft, for the purposes described.
5. In a turbine, a casing, rotatable parts acted upon by the motor fluid therein, a compound throttling packing between said casing and parts at the high pressure end of the turbine and comprising inner and outer members, passages leading from said packing to different points in the turbine, and an automatic pressure controlled means to adjust said outer member to govern the distribution of leakage fluid through said passages into the turbine.
6. In a turbine, a casing, rotatable parts therein, a high pressure packing between said parts and casing in which the leakage fluid is expanded through a series of annular chambers, means to govern the pressure in said chambers, passages leading from the several chambers to different points in the turbine where slightly lower pressures obtain, and means to cause said passages to discharge substantially equal weights of leakage fluid from each chamber into the turbine.
7. In a turbine, a casing, rotatable parts therein, and a compound throttling packing for said parts at the high pressure end of said casing, said packing comprising rotatable and non-rotatable elements, means to adjust the non-rotating element and the clearances between said elements and passages leading into the turbine from openings in said packing which passages are so disposed as to be valved as said elements are adjusted to close the clearances in said packing.
8. In a turbine, a casing, rotatable parts therein, and a packing for said parts at the high pressure end of said casing, said packing comprising rotatable and non-rotatable ring projections, passages leading from the rotatable projections at points where they will be valved by the non-rotatable projections and which enter the turbine, and means to adjust the non-rotating projections in an axial direction.
9. In a turbine, rotatable parts, a high pressure packing therefor comprising rings rotatable with said parts, normally fixed rings co-acting with said rotatable rings, means to adjust the clearances between said rings, an annular groove in the side face of one or more of said rings, and one or more passages leading from each of said grooves into the turbine, said grooves being disposed in a position to be valved by an adjacent ring for the purposes described.
10. In a turbine, a head having a shaft opening therein, a shaft projecting through
- said opening, a self adjusting throttling packing between said shaft and head comprising a rotating and a stationary element, a liquid seal exterior to said packing and exposed to the pressure leaking past said packing, and a fluid motor for automatically adjusting the stationary element of said packing which is controlled by leakage fluid, the pressure of which is normally less than the difference in pressures between which the liquid seal is adapted to act.
11. In a turbine, a casing having a shaft opening, a shaft projecting through said opening, a throttling packing comprising annular projections rotatable with the shaft, annular projections carried by the casing, an annular chamber surrounding the shaft exterior to said packing, an element rotatable with the shaft and adapted to act on a body of liquid in said chamber as a packing means, passages leading from different points in and beyond said throttling packing to return leakage fluid into the turbine, and means to adjust the annular projections carried by the casing to govern both the volume of leakage through the packing and the distribution of the leakage fluid in the turbine.
12. In a turbine, a casing, rotatable parts therein, a shaft supporting said parts, a high pressure compound throttling packing for said shaft comprising a plurality of chambers that receive leakage fluid, passages leading from two or more of said chambers to return leakage fluid to different points in the turbine, the passages increasing in number for the chambers toward the low pressure end of the packing.
13. In a turbine, a casing, rotatable parts therein, a shaft supporting said parts, a high pressure compound throttling packing for said shaft comprising a plurality of chambers through which the leakage fluid flows in succession, and means to discharge substantially equal weights of leakage fluid from said chambers into the turbine which increase in capacity toward the low pressure end of said packing.
14. An elastic fluid turbine comprising an outer casing, a head and a plurality of diaphragms having flanged peripheries which interlock and form an inner casing, abutments carried by the outer casing between which the sectional inner casing is held together, the inner casing increasing in diameter toward the exhaust end, and a chamber formed between the inner and outer casing opposite the high pressure diaphragms.
15. An elastic fluid turbine comprising an outer casing divided into sections on a longitudinal plane, an inner casing divided into sections on transverse planes, and abutments carried by the outer casing which engage and hold the sections of the inner

casing together between them, as and for the purposes described.

16. An elastic fluid turbine comprising an outer casing of substantially uniform diameter, an inner sectional casing of increasing diameter toward the exhaust end of the turbine, said outer casing being adapted to hold the sections of said inner casing together and leave an annular chamber be-

tween the casings at the high pressure end 10 of the turbine.

In witness whereof, I have hereunto set my hand this 10th day of October, 1911.

JAMES WILKINSON.
